UNITED STATES PATENT OFFICE.

ARTHUR R. HAVENER, OF WAYLAND, MASSACHUSETTS, ASSIGNOR TO JUDSON L. THOMSON MANUFACTURING CO., OF WALTHAM, MASSACHUSETTS, A CORPORATION OF MASSACHUSETTS.

RIVET-SETTING MACHINE.

Application filed March 21, 1927. Serial No. 176,905.

This invention relates to a rivet setting machine and particularly to a machine for riveting corrugated metal reinforcing strips to metal ash receptacles or the like.

5 The object of the invention is to provide a simple, efficient and powerful machine of the character set forth, in which the work rests upon a combined anvil and punch die, said anvil embodying therein a movable central member which recedes during the rivet inserting operation to form a die opening in said anvil, thereby permitting the driver to force the rivet through the work, after which said central member is moved upwardly into 10 position to co-operate with the other or main portion of the anvil in clinching said rivet to the work.

It is further an object of the invention to so construct the driving mechanism that the 20 driver thereof will have two driving strokes imparted thereto during each cycle of the machine, the first or main stroke engaging a rivet in the rivet carrier and forcing said rivet from said carrier through the work, the 25 rivet punching its hole in the work as it is forced downwardly therethrough, and the final stroke being relatively short as compared to the initial stroke and engaging the head of the rivet and causing said rivet to be 30 clinched to said work.

The invention consists in a machine for setting rivets in sheet metal as set forth in the following specification and particularly as pointed out in the claims thereof.

35 Referring to the drawings:

Figure 1 is a front elevation of a rivet setting machine embodying my invention.

Fig. 2 is a side elevation of the machine as viewed from the left of Fig. 1.

40 Fig. 3 is a side elevation of the machine as viewed from the right of Fig. 1.

Figs. 4, 5, 6 and 7 are enlarged detail sectional elevations illustrating different positions of the rivet inserting and clinching mechanisms.

45 Fig. 8 is a perspective view of the rocker cam.

Fig. 9 is a detail view illustrating a corrugated reinforcing strip attached to a portion of a receptacle.

Like numerals refer to like parts throughout the several views of the drawings.

In the drawings, 10 is the frame of the ma-

chine and 11 is a driving shaft journalled to rotate in suitable bearings 12 and 13 in said frame. Fast to the driving shaft 11 is a pinion 14 which meshes with a gear 15 journalled to rotate upon a shaft 16, said gear forming one member of a clutch 17. Another member 18 of said clutch is rigidly fastened to the 55 shaft 16. The two members 15 and 18 are clutched together as one piece by a suitable mechanism not shown in the drawings, but well known to those skilled in the art, this mechanism being operated from a treadle, 60 not shown in the drawings, by means of a treadle rod 19.

The rivets are driven during the setting operation by a driver 20 which is fastened to a slide 21 guided in ways 22 in the frame 10. 70 The slide 21 has a vertical reciprocatory motion imparted thereto by a pair of toggle links 23 and 24 which are connected to a connecting rod 25 by a pivotal pin 26. The link 24 is pivoted at 27 to the frame 10 of the 75 machine, while the link 23 is connected to the upper end of the slide 21 by a pin 28. The connecting rod 25 is pivotally connected at its opposite end to a crank pin 29 which is fastened to a cam 30, said cam being in turn 80 fastened to the shaft 16. By this mechanism a reciprocatory motion is imparted to the slide 21 and hence to the driver 20.

The rivets are fed from a hopper 31 down a raceway 32 and are separated by a slide 33 to be fed down a raceway 34 into a carrier 35 which consists of two carrier members 36 and 37 fast to springs 38 and 39 respectively, said springs being fastened by a bolt 40 to a carrier slide 41. The carrier slide 41 has a pin 42 fast thereto which projects through a slot 43 in the frame of the machine and constitutes a stop to limit the upward movement of the slide 41. The slide 41 also has a pin 44 fast thereto, which projects into a slot 45 in the lever 46, which is pivoted at 47 to the frame of the machine, and at its opposite end said lever is provided with a cam roll 48 which bears against the periphery of the cam 30. A spring 49 is fastened at one end to the lever 46 and at its other end to the frame 10 and acts to hold the roll 48 in engagement with the cam 30 during its operation.

Rivets 83 are transferred from the raceway 32 to the raceway 34, one at a time, by the slide 38 which is operated by a lever 50

pivoted at 51 to the frame of the machine, and has a rocking movement imparted thereto in one direction by a spring 52 and in the opposite direction by a projection 53 on the rear side of the connecting rod 25.

The operation of the slide 33 in transferring the rivets 83 from the raceway 32 to the raceway 34 is well known to those skilled in the art, and as it forms no part of this 10 invention requires no further description.

An anvil member 54 also constituting a work support is mounted in a block 55, in turn fastened to an arm 56 forming a part of the frame of the machine. The block 55 is rigidly secured to said arm 56 by screws 57, and said arm has a groove 58 extending thereacross, in which a portion 59 of said block is positioned. An end 60 of the arm 56 provides a rigid abutment against which the block 55 is braced, thereby providing a very rigid support for the anvil member 54. The anvil member 54 may be adjusted vertically in the block 55 by manipulating a nut 61 and check nut 62, after which said anvil 25 is secured in place by a set screw 63. The anvil member 54 is recessed at its upper extremity at 64 to provide a clinching surface for said anvil, and the latter also has a bore 65 formed therein in which an auxiliary anvil member 66 is slidably mounted. The member 66 is shouldered and extends through an opening 67 which constitutes a punch die, and the upper extremity of said member 66 has an anvil portion 68 formed thereon, 30 which co-operates with the recessed surface 65 of the anvil member 54 to form the clinching surface against which the rivet is forced 35 during the clinching operation.

The member 66 recedes or drops downwardly for the rivet inserting operation, but is forced upwardly prior to the clinching operation by a cam 69 which is pivoted at 70 to the block 55, and said cam is slotted at 71 to form arms 72 and 73, the former having cam surfaces 74 and 75 formed at its upper extremity.

A rocking movement is imparted to the cam 69 by a connecting rod 76 which is connected at one end thereof at 77 to said cam and at its other end at 78 to one end of a lever 79, the latter being pivoted at 80 to the frame 10. The other extremity of the lever 79 has a cam roll 81 mounted thereon, said roll projecting into a cam groove 82 formed 55 in the side of the cam 30. As the lower portion of the cam 69 is moved forwardly by its operating mechanism, the portion 74 of said cam is positioned beneath the lower extremity of the member 66, as illustrated in Fig. 4, and the latter will either drop of its own weight or will recede during the rivet inserting operation to permit a rivet to be forced through the work as illustrated in Fig. 5, the opening 67 provided at the top 60 of the anvil 55 by the receding movement of

the member 66 forming a die opening in said anvil. The cam 69 is then rocked by its operating mechanism to force the anvil member 66 upwardly until the cam portion 75 is located beneath said member 66 as illustrated in Fig. 6, at which time the anvil portion 68 at the top of said member 66 is positioned to co-operate with the recessed portion 64 of the anvil member 54 in performing the clinching operation.

The general operation of the mechanism hereinbefore specifically described is as follows:—Assuming the various parts to be in the relative positions illustrated in Figs. 1 to 4 inclusive, a receptacle A, having a corrugated metal reinforcing strip a positioned thereon, is positioned upon the anvil member 54 as illustrated in Fig. 1. The machine is then started by means of a treadle, not shown, and its connecting rod 19 which causes the clutch 17 to rotate the shaft 16 and thus the rivets 83 are fed down the raceways 32 and 34 to be delivered one by one into the rivet carrier 35.

In Fig. 4 a rivet 83 is shown in position in the rivet carrier 35 ready to be driven by the driver 20. The rivet carrier 35, carrying the rivet 83, now moves downwardly to a point just above the work and the driver 20 also moving downwardly engages the rivet 83 in said carrier forcing said rivet through said carrier in a manner well known to those skilled in the art and through said work, the prongs of said rivet projecting into the die opening 67 of the anvil member 54 as illustrated in Fig. 5.

When the driver 20 reaches the bottom of its stroke, during the rivet inserting operation, the axes of the pins 26, 27 and 28 are all located in alignment with the center line of the driver 20, but instead of immediately retreating, the connecting rod 25 continues to move forwardly until at its extreme forward movement the crank pin 29 has moved said connecting rod to position the toggle links 23 and 24 as illustrated in dotted lines in Fig. 2, and during the latter part of this forward movement the connecting rod 26 has caused said toggle links to lift the driver slide 21 and driver 30 so that the latter will be positioned as illustrated in Fig. 6.

The cam 69 is now rocked by its actuating mechanism to lift the anvil member 66 and position the upper extremity 68 thereof into co-operative relation with the surface of the recess 64 of the anvil member 54 as illustrated in Fig. 6, and the driver 20 will again descend with the first portion of the retreating movement of the connecting rod 25, causing the rivet to be clinched as illustrated in Fig. 7. A continued retreating movement of the connecting rod 25 will again cause the driver 20 to move upwardly releasing the work, so that it may be removed from the anvil, and the cam 69 is again actuated to permit the mem- 120 125 130

ber 66 to recede into the anvil 54 preparatory to another cycle of operations as previously mentioned.

The rivets illustrated as being utilized in connection with the machine of this invention are of the well-known bifurcated type, but it is evident that other forms of rivets, such as, the tubular and solid types may be utilized without departing from the spirit 10 of the invention, all of said types of rivets being forced through the work and either clinched or upset by the mechanism set forth.

I claim:—

1. A machine for setting rivets in sheet metal having, in combination, an anvil embodying therein a stationary member and a movable member, the latter being adapted to recede during the rivet inserting operation to form a die opening in said anvil, means 20 to position said movable member into co-operative relation with said stationary member to clinch a rivet, and a driver adapted to co-operate with said anvil to first force a rivet through said sheet metal and finally to clinch said rivet thereto.

2. A machine for setting rivets in sheet metal having, in combination, an anvil provided with a rivet clinching surface and embodying therein a central movable member, the latter being recedeable to form a die opening for said anvil, said movable member having a portion of said clinching surface formed thereon, means to position said movable member to close said opening and render said clinching surface operable, and a driver adapted to co-operate with said anvil to force a rivet through said sheet metal and clinch said rivet thereto.

3. A machine for setting rivets in sheet metal having, in combination, an anvil provided with a rivet clinching surface and embodying therein a central movable member, the latter being recedeable to form a die open-

ing for said anvil, said movable member having a portion of said clinching surface formed thereon, a cam engaging said movable member and adapted to position the latter to close said opening and render said clinching surface operable, and a driver adapted to co-operate with said anvil to first force a rivet 45 through sheet metal and finally to clinch said rivet thereto.

4. A machine for setting rivets in sheet metal having, in combination, an anvil provided with a rivet clinching surface and embodying therein a central movable member, the latter being recedeable to form a die opening for said anvil, said movable member having a portion of said clinching surface formed thereon, a cam engaging said movable member, means to impart a rocking movement to said cam, whereby said movable member is positioned to close said opening and render said clinching surface operable, and a driver adapted to co-operate with said anvil to first 50 force a rivet through sheet metal and finally to clinch said rivet thereto.

5. A machine for setting rivets in sheet metal having, in combination, an anvil embodying therein a stationary member and a 70 movable member, the latter having an anvil portion formed upon its upper extremity and being adapted to recede within said stationary member during the rivet inserting operation and thereby provide a die opening in said 75 anvil, means to advance said movable member to position the anvil portion thereof into co-operative relation with said stationary member to clinch a rivet, and a driver adapted to co-operate with said anvil to first force 80 a rivet through said sheet metal and finally to clinch said rivet thereto.

In testimony whereof I have hereunto set my hand.

ARTHUR R. HAVENER.
